UNITED STATES PATENT OFFICE.

HARRY R. KELSEY AND DALLAS B. BENHAM, OF MINNEAPOLIS, MINNESOTA.

SPARK-PLUG.

1,326,599.

Specification of Letters Patent. Patented Dec. 30, 1919.

Application filed February 7, 1916. Serial No. 76,574.

To all whom it may concern:

Be it known that we, HARRY R. KELSEY and DALLAS B. BENHAM, citizens of the United States, residents of Minneapolis, 5 county of Hennepin, State of Minnesota, have invented certain new and useful Improvements in Spark-Plugs, of which the following is a specification.

The object of our invention is to provide 10 a spark plug having a sparking surface of comparatively large area and a neutral member insuring the formation of a multiplicity of sparks and the ignition of the charge in the cylinder.

15 A further object is to provide a plug having sparking surfaces which can be easily and quickly removed for cleaning or repairing.

Other objects of the invention will appear 20 from the following detailed description.

The invention consists generally in various constructions and combinations, all as hereinafter described and particularly pointed out in the claims.

25 In the accompanying drawings forming part of this specification,

Figure 1 is an elevation of a spark plug embodying our invention,

Fig. 2 is a vertical sectional view of the 30 same,

Fig. 3 is a perspective view of the outer sleeve forming one of the electrodes,

Fig. 4 is a sectional view on the line $x-x$ of Fig. 2.

35 In the drawing, 2 represents the metallic plug that is tapped into the wall of the cylinder in the usual way and seated on the gasket 3. The plug is hollow, as usual in devices of this kind, and is adapted to

40 receive an insulating member 4 of porcelain or other suitable material. This member 4 has a collar 5 formed thereon and a shoulder 6 is provided in the plug 2 between which and the collar 5 suitable material,

45 such as asbestos 7, is placed. The outer end of the plug 2 is interiorly threaded to receive a nut 8 which is exteriorly threaded to engage the threads of the plug and is seated at its lower end against the collar 5 to clamp the member 4 securely against the shoulder 6.

Within this insulating member 4 is mounted an electrode bolt 9 projecting through the insulating material at each end 55 and threaded at its outer end to receive the thumb nut 10, between which and the nut

11 the conductor of the electric current is clamped. Within the open inner end of the plug 2 a sleeve is arranged, consisting of rings 12 and 13 connected with one another by bars 14, the ring 13 having an annular rib 15 formed thereon that is adapted to enter a correspondingly shaped recess 16 in the inner surface of the plug, said ring being divided transversely at 17 to permit it 60 to be compressed or contracted sufficiently to enter the open end of the plug and when it is inserted into the plug and released, the ring will expand and engaging the walls of the recess, will be held temporarily 65 therein, but may be easily and quickly removed by grasping the inner end of the sleeve.

The walls of the sleeve are in circuit with the cylinder through the metal plug, as 70 usual in spark plugs, and the ring 12 has a circular sparking surface 18 concentric with the electrode bolt 9. We have shown this sleeve removably mounted in the plug, but it may be formed as a continuation of 75 the walls of the plug, if preferred. This, however, would be an obvious modification and I have not thought it necessary to illustrate it herein, as the change would merely consist in extending the threaded end of 80 the plug to a point opposite the end of the electrode bolt.

A second sleeve 19 is provided, fitting 85 within said first named sleeve and having an open upper end adapted to receive the 90 recessed end 20 of the insulating member 4, and there is sufficient friction between the sleeve and the insulating member to hold the sleeve in place thereon. The lower end of the sleeve 19 is encircled by the sparking surface 18 of the outer sleeve and a narrow gap is formed between them. Said sleeve 19 has a ring 21 forming a sparking surface and provided with a central opening 22 into which the electrode bolt 9 projects, said bolt being spaced from the surface of the ring a sufficient distance to insure the formation of a multiplicity of sparks between it and the ring 12 and thereby greatly increase the certainty of ignition 95 of the charge in the cylinder.

We prefer to designate the sleeve 19 as the neutral member of the plug, as it has an insulating bearing on the part 4 and its ring 21 partially bridges the gap between the 100 electrode bolt and the surface 18 and provides for a large increase in the sparking

area or surface, there being, of course, a group of sparks formed between the bolt and the ring 21 and another group between the ring 21 and the surface 18.

5 The sleeves have openings therein forming passages through which the fresh charge of gas as it enters the cylinder may circulate, and all of the insulating surfaces are remote from the sparking surfaces and consequently 10 the accumulation of carbon on these surfaces, which we have found will take place when they are adjacent to an insulating surface or no circulation of the fresh gas around them is provided for, will be entirely 15 eliminated and the sparking surfaces will remain remarkably clean under all conditions.

20 This plug is of extremely simple construction, the members having the sparking surfaces are easily accessible, and can be readily removed for cleaning or repairing without disturbing the other connections of the 25 plug.

We claim as our invention:

- 25 1. A spark plug comprising a conducting member having means for mounting it in an engine cylinder, an insulating member fitting within said conducting member, a pin-shaped electrode mounted in said insulating member and projecting beyond the inner end thereof, sleeves concentrically arranged and mounted respectively on said conducting member and said insulating member, said sleeves being provided with annular sparking surfaces, the sparking surface of the inner sleeve encircling and being equi-distant substantially from the end of said electrode and the sparking surface of said outer sleeve encircling the corresponding surface of said inner sleeve and being uniformly spaced from said sparking surface, whereby annular gaps are formed between said electrode and said inner sleeve and between said sleeves for evenly distributing the current 30 and providing a multiplicity of sparks between said electrode and said surfaces, said sleeves having openings in their walls and the annular gaps between said sparking surfaces being unobstructed to allow the free circulation of the fuel gas between them.
- 35 2. A spark plug comprising a conducting member having means for mounting it in an engine cylinder, an insulating member fitting within said conducting member, an electrode mounted in said insulating member and projecting beyond the inner end thereof and sleeves concentrically arranged and mounted respectively on said conducting

50 meinber and said insulating member, said sleeves having annular, inwardly projecting ribs formed thereon, provided with sparking surfaces, the surfaces of the rib of said inner sleeve encircling and being equi-distant substantially from the end of said electrode, and the sparking surface of said outer sleeve encircling the corresponding surface of said inner sleeve and being uniformly spaced from the outer walls of said inner sleeve, whereby annular gaps are formed between said electrode and said inner sleeve 55 and between said sleeves for evenly distributing the current and providing a multiplicity of sparks between said electrode and said surfaces.

5. A spark plug comprising a conducting member adapted for mounting it in an engine cylinder, an insulating member fitting therein, a pin-shaped electrode centrally mounted in said insulating member, an active electrode mounted in said conducting member and having a sparking surface encircling said pin-shaped electrode, a neutral electrode having a sparking surface encircling said pin-shaped electrode and spaced therefrom, said neutral electrode being encircled by said active electrode and spaced therefrom, whereby concentrically arranged air gaps will be formed between said electrodes to provide a multiplicity of sparks, and said gaps being unobstructed for a free circulation of fuel gas through them and through and between said active and neutral electrodes.

4. A spark plug comprising a conducting member adapted for mounting it in an engine cylinder, an insulating member fitting therein, a pin-shaped electrode mounted in said insulating member, an active electrode mounted in said conducting member and having a sparking surface encircling said pin-shaped electrode, a neutral electrode having a sparking surface encircling said pin-shaped electrode and spaced therefrom, said neutral electrode being encircled by said active electrode and spaced therefrom, whereby air gaps will be formed between said electrodes to provide a multiplicity of sparks, and said gaps being unobstructed for a free circulation of fuel gas through them and through and between said active and neutral electrodes.

In witness whereof, we have hereunto set our hands this 3d day of January 1916.

HARRY R. KELSEY.
DALLAS B. BENHAM.
